DOOR LOCK

Allan C. Hubbell, Long Beach, Calif.

Application June 10, 1936, Serial No. 84,580

4 Claims. (Cl. 70—149)

This invention relates to door locks and the object of the invention is to provide a lock which may be used on the doors of automobiles, airplanes, boats, and analogous vehicles, or on the doors of buildings and the like.

A further object of the invention is to provide a door lock of the character mentioned which may be operated from either side of the door and which may be operated from the inside of the door for locking the door against being opened by an unauthorized person from the outside.

A further object of the invention is to provide a lock of the character above mentioned which, while the same may be locked from inside the door without resort to a key, a key will be required for unlocking the door from the outside thereof.

The invention together with its objects and advantages will be best understood from a study of the following description taken in connection with the accompanying drawings wherein:

Figure 1 is an elevational view of the complete lock assembly.

Figure 2 is an elevational view of the lock with cover plate removed and with the inner handle in a normal or unlocked position.

Figure 3 is a horizontal sectional view with the parts positioned as shown in Figure 2.

Figure 4 is a fragmentary view somewhat similar to Figure 2 with the inside handle in locked position.

Figure 5 is a view somewhat similar to Figure 4 and showing the parts in position for retracting the bolt by the operation of the handle at the inside of the door.

Figure 6 is a horizontal sectional view showing the bolt in retracted position and the parts in the position occupied thereby when the bolt is retracted by manipulation of the outside handle.

Figure 7 is a vertical sectional view through the lock.

Figure 8 is a horizontal sectional view showing in full lines the bolt in projected position and the parts in the position occupied for transmitting movement of the outside handle to the bolt for retracting the latter, and also showing in dotted lines the bolt in retracted position and the parts in the position occupied thereby when the bolt is retracted by manipulation of the outside handle.

Figure 9 is a view similar to Figure 8 with the bolt in projected position and showing the parts in the position occupied as will preclude retraction of the bolt by manipulation of the outside handle.

Figure 10 is a vertical sectional view of one

compartment taken substantially on the line 10—10 of Figure 2 and showing the slide member in raised position.

Figure 11 is a view similar to Figure 10 but with the slide member in lowered position.

Figure 12 is a fragmentary detail sectional view showing the location and provision of a clip for locking the inside handle in the position shown in Figure 4.

Figure 13 is a side elevational view of the slide member.

Figure 14 is a side elevational view of a bearing bracket.

Figure 15 is an edge elevational view of the bearing bracket.

Figure 16 is a perspective view of a spring biased member hereinafter more fully referred to.

Figure 17 is a side elevational view of a lug-equipped male member hereinafter more fully referred to.

Figure 18 is a perspective view of the bolt.

Figure 19 is a perspective view of a horizontally slidable member hereinafter more fully referred to.

Figure 20 is a perspective view of a bracket hereinafter more fully referred to.

Referring to the drawings by reference numerals it will be seen that in the preferred embodiment thereof the door lock comprises a suitable casing 1 divided into a pair of compartments 2 and 3 respectively through the medium of a partition plate 4. Provided in the compartment 2 are upper and lower guide members 5 between which as clearly shown in Figures 2 and 7 is slidably mounted a locking bolt 6 that is normally urged to a projected position through the medium of a suitable spring device 7.

For the inside of the door lock is a handle 33 which as best shown in Figure 7 is secured to one end of a stud 31 journaled in a suitable bearing 32 provided therefor at the inner side of the casing 1. The stud 31 has a squared end that extends into the compartment 2 and on said squared end there is provided a male head 30. Head 30 has suitably associated therewith a lug 38 which as shown in Figure 5 moves into engagement with a lug 42 on the bolt 6 incidental to a swinging movement of the handle 33 in a counter-clockwise direction for retracting the bolt 6 from the inside of the door with which the lock is associated.

Further in accordance with the present invention there is arranged for sliding movement in the compartment 3 a slide block 8 that is normally urged in one direction through the medium of a suitable spring device 9.

As clearly shown in Figure 6 slide block 8 has secured at one side thereof through the medium of bolts 12 an abutment block 11 that operates within a channel 10 provided therefor in the bolt 6.

In this connection it will be noted that the partition 4 is provided with a slot 4a to accommodate the bolts 12.

Mounted for vertical sliding movement in the compartment 2 is a slide plate 13 having a reduced lower end that works vertically through a slot 14 provided in the bolt 6 adjacent one end of the channel 10. The slide plate 13 is normally urged upwardly through the medium of a member 15 preferably of the shape and construction shown in Figure 16 and which member is provided with pintles 16 journaled in the apertured lugs 17 of a bracket 18 suitably secured in the upper portion of the compartment 2 as best shown in Figure 2. The member 15 is normally urged to swing upwardly through the medium of a suitably anchored spring 19, and said member 15 has a part thereof engaging in a notch 20 in the upper portion of the slide 13 as shown in Figures 10 and 11 for transmitting movement of the member 15 to the slide 13.

In Figure 10 the member 13 is shown in its raised position and as shown in Figure 6 when the member 13 is in raised position it provides an abutment for the block 11. Thus when the member 13 is in raised position it will be seen that a sliding movement of the block 8 towards the right in Figure 6 will cause the block 11 to abut the member 13 so that the movement of the block 8 in the direction indicated will be transferred to the bolt 6 for retracting the latter.

For moving the slide block 8 in the direction above referred to for retracting bolt 6 there is provided at the outer side of the door or lock casing a handle 23 that has an end portion pivoted as at 24 within a suitable recess R provided therefor in the outer wall of the lock casing 1. At the pivoted end thereof the handle 23 is provided with an integral projection or dog 25 which engages a notch 26 formed at one end of the block 8. Thus it will be seen that with the slide 13 in its raised position an outward swinging movement of the handle 23 to the position shown in Figure 6 will in a manner just explained result in a retraction of the bolt 6.

From the above it will be seen that through the medium of the handle 33 bolt 6 may be retracted from the inner side of the door and through the medium of the handle 23 bolt 6 may be retracted from the outer side of the door.

For securing the bolt 6 against being retracted by manipulation of the handle 23 there is provided on the male head 30 a lug 37 which, when the handle 33 is swung from the position shown in Figure 2 to the position shown in Figure 4, will engage an extension 35 of the member 15 for causing the member 15 to move downwardly thus causing the slide plate 13 to move downwardly. In this connection, and as shown in Figure 4, it will be noted that as the lug 37 engages the extension 35 of member 15 for forcing the latter downwardly against the action of spring 19 lug 38 associated with the head 30 moves upwardly into engagement between spring jaws 39 suitably mounted in compartment 2 for securing the handle 33 in the position shown in Figure 4.

When the member 13 is caused to move downwardly in the manner just mentioned the slot or notch 21 in said member will align with the channel 10 so that the member 13 will now offer no

resistance to the block 11. Thus with the member 13 in the lowered position it will be seen that handle 23 may be manipulated for sliding the block 8 to the position shown in Figure 9 without effecting a retraction of the bolt 6. This is due to the fact that, of course, the block 11 will merely pass through the notch portion 21 of the slide 13 and thus no movement of the block 8 will be transmitted to the bolt 6.

Manifestly for unlocking the door to permit a retraction of the bolt 6 incidental to a manipulation of handle 23, handle 33 is returned substantially to the position shown in Figure 2.

Also in accordance with the present invention there is suitably mounted on the outer cover plate 15 of casing 1 a key-controlled lock 27 which includes among other parts a key-operated bolt 28 that extends through partition 4 into the compartment 2. On the squared portion of the bolt 28 is a female head member 29 which receives in the socket portion thereof a part of the male head 30 as shown in Figure 7.

In connection with the above it will of course be understood that member 29 rotates with the bolt 28 relative to the head 30. Member 29 is provided with an integral lug 41 as shown in Figures 2, 4 and 5.

It will thus be seen that when it is desired to set the lock from the outer side of the door to prevent retraction of the bolt 6 the key 40 is inserted into the lock 27 and the bolt 28 rotated in a clockwise direction. This will result of course in head 29 rotating with the bolt for moving the lug 41 associated with the head into engagement with the extended end 35 of the member 15. Thus lug 41 engaging said end 35 of member 15 will cause the latter to move downwardly against the action of spring 15 for placing the slide 13 in the position shown in Figure 11.

As previously pointed out with the slide 13 in its lower position handle 23 may be manipulated for moving the slide 8 against the action of spring 9 without in any way effecting a retraction of the bolt 6.

For locking the parts shown in the position in Figure 5, and to which position they were moved incidental to a turning of the key 40 in the lock 27 as just described, there is suitably mounted in the compartment 2 and on the partition 4 a spring projected catch 43 which engages a socket 44 provided in the cylindrical part of the member 29 as shown. In this connection it will also be noted that the cylindrical part of member 29 diametrically opposite to the socket 44 is provided with a second socket 44a with which the catch 43 engages for releasably locking the member 29 and associated parts in the position shown in Figure 2.

With the head 29 locked in the position shown in Figure 5 member 15 will be held in the downward position shown in Figure 5 so that as just mentioned the assembly is locked in a manner to preclude an opening of the door, or in other words a retraction of the bolt 6 by manipulating the handle 23 at the outer side of the door. Obviously, to unlock the door from the outer side thereof key 40 is turned in a reverse direction, or in a counter-clockwise direction causing the head 29 to move in a corresponding direction from the position shown in Figure 5 to the position shown in Figure 2 thus permitting the member 15 to move upwardly under action of spring 15 for raising the slide plate 13 so that the same will now present an abutment to the abutment block 11. Upon return of head 29 to the position shown

in Figure 2, catch 43 will engage the socket 44a as shown in said Figure 2 for locking the head 29 in the position illustrated in said figure.

A bearing bracket 36 depends from the top of the compartment 2 and is provided with an opening 38' which accommodates the cylindrical part of the head 30 as shown in Figure 7. In one edge thereof the bracket 36 is provided with a notch 36a for the purpose of allowing lug 37 clearance when the inner handle is used for retraction of bolt 6.

Since the manner in which the device operates was pointed out in the detailed description of the parts it is thought unnecessary to again set out in detail the operation. Suffice it to say that a lock constructed in accordance with the present invention may have the bolt thereof retracted from either the inner side or outer side of the door with which the lock is associated, or said bolt may be disconnected from the operating means therefor at either the inner side or outer side of the door to the end that a substantially fool-proof lock is provided.

Having thus described the invention what is claimed as new is:—

1. In a lock of the character described, a casing, a bolt slidably mounted in the casing, spring means engaged with the bolt for projecting it, a slide block mounted in the casing laterally of the bolt, spring means engaged with the slide block for normally urging it in one direction, a plate mounted for vertical sliding movement through a slot in said bolt, an abutment block mounted on one side of the slide block for movement therewith and engageable with said vertically movable plate when the latter is in raised position for transmitting movement of the slide block to the bolt for retracting the latter, handle means at one side of the casing and engaging the slide block for moving it in a direction to retract said bolt, and means operable from either side of the casing for lowering said plate, and means connected with said plate for normally urging it to a raised position.
2. In a lock of the character described, a casing, a bolt mounted in the casing, for sliding movement, spring means engaged with the bolt for normally urging the same to a projected position, a block slidably mounted in the casing and disposed laterally of the bolt, a slide plate mounted for vertical movement within the casing through a slot in said bolt, said bolt being also provided with a longitudinal channel intersecting said slot, an abutment block carried by and disposed laterally of the slide block and working in said channel for engagement with said vertically slidable plate when the latter is in raised position whereby to transmit movement of the slide block to the bolt for retracting the latter, a member pivotally mounted within the casing and engaged with the vertically slidable plate for normally urging the latter upwardly, and means operable from either side of the casing for moving the slide plate downwardly out of the path of the abutment block in-

cluding means for releasably securing the vertically slidable plate in its lowered position.

3. In a lock of the character described, a casing, a bolt slidably mounted in the casing, spring means connected with the bolt and normally urging the same to a projected position, said bolt being provided with a longitudinal channel and a vertical slot intersecting the channel, a slide plate movable vertically through said slot, said slide plate being provided with a notch adapted to align with the channel when the slide plate is in lowered position, a block mounted for sliding movement within the casing at one side of said bolt, an abutment block carried by the slide block and working in said channel to engage the vertically slidable plate when the latter is in raised position for transmitting movement of the slide block to the bolt for retracting the latter, handle means mounted at one side of the casing and engaging the slide block for moving the latter in one direction for retracting the bolt, spring means connected with the vertically slidable plate for normally urging the latter upwardly, handle means at the side of the casing opposite to the first named handle and having means engageable with the bolt for retracting it, when the second named handle means is rotated in one direction, and also having means for forcing the slide plate downwardly when the second named handle means is swung in a reverse direction.

4. In a lock of the character described, a casing, a bolt mounted for sliding movement in the casing, spring means engaged with the bolt for normally projecting the latter, a block slidably mounted in the casing laterally of the bolt, said bolt being provided with a longitudinal channel and a vertical slot intersecting the channel, a vertically movable slide plate mounted in the casing and movable through said slot, said slide plate being provided with a notch aligning with the channel when the slide plate is in a lowered position, a spring device connected with the slide plate for normally urging the same to a raised position, means on said slide block and working in the channel of the bolt for engaging the slide plate when the latter is in a raised position for transmitting movement of the slide block to the bolt for retracting the latter, a handle mounted on one side of the casing, inter-engaging means on said handle and the slide plate for moving the slide plate downwardly upon rotation of said handle in one direction for placing the notch in the slide plate in alignment with said channel, whereby said bolt will be retained in projected position against retraction incidental to a sliding movement of said block, said first mentioned handle means and said bolt having inter-engaging means for retracting the bolt incidental to a movement of the handle in a reverse direction, and handle means at the second mentioned side of the casing engageable with said block for operating the latter to retract the bolt when said slide plate is in its raised position.

ALLAN C. HUBBELL.
